UNITED STATES PATENT OFFICE.

LOUIS J. FREUNDT, OF CHICAGO, ILLINOIS, ASSIGNOR TO AMERICAN CAN COMPANY, OF NEW YORK, N. Y., A CORPORATION OF NEW JERSEY.

DESIGN FOR A SHEET-METAL CADDY-BODY BLANK.

No. 39,784.

Specification for Design.

Patented Jan. 19, 1909.

Application filed July 15, 1908. Serial No. 443,741. Term of patent 14 years.

To all whom it may concern:

Be it known that I, LOUIS J. FREUNDT, a citizen of the United States, residing at Chicago, in the county of Cook and State of Illinois, have invented a new, original, and ornamental Design for a Sheet-Metal Caddy-Body Blank, of which the following is a specification, reference being had to the accompanying drawing, forming a part thereof.

The figure is a front elevation of a sheet

metal display caddy body blank in the flat, showing my new design.

I claim:

The ornamental design for a sheet metal caddy body blank, as shown.

LOUIS J. FREUNDT.
